United States Patent Office

Des. 198,779
Patented Aug. 4, 1964

198,779

TEPEE

Pat M. Bredon, 3518 Crittenden, St. Louis 18, Mo.

Filed Oct. 16, 1963, Ser. No. 76,999

Term of patent 14 years

(Cl. D13—1)

FIG. 1

FIG. 2

FIG. 3

FIG. 1 is a front elevational view of the tepee, showing my new design;

FIG. 2 is a rear elevational view thereof; and

FIG. 3 is a top plan view thereof.

I claim:

The ornamental design for a tepee, as shown.
